CLAIM

The ornamental design for a smart safe, as shown and described.

DESCRIPTION

FIG. 1 is a front, right and top perspective view of a smart safe, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged portion view taken from encircled portion, "9," in FIG. 1.

The dot-dashed broken lines shown in FIGS. 1 and 9 illustrate the boundary lines of the enlarged portion view of FIG. 9 and forms no part of the claimed design. The even dashed broken lines shown in the drawings represent portions of the safe that form no part of the claimed design.
